UNITED STATES PATENT OFFICE

120,919

DESIGN FOR A COMBINED RADIO AND LAMP

Maurice Ress, Brooklyn, N. Y.

Application January 9, 1939, Serial No. 82,251

Term of patent 3½ years

To all whom it may concern:

Be it known that I, Maurice Ress, a citizen of the United States, residing in the Borough of Brooklyn, county of Kings, and city and State of New York, have invented a new, original, and ornamental Design for a Combined Radio and Lamp, of which the following is a specification, reference being had to the accompanying drawing, forming part thereof.

On the drawing:

Fig. 1 is a front elevational view of a combined radio and lamp showing my new design;

Fig. 2 is an end elevational view of the combined radio and lamp shown in Fig. 1; and
Fig. 3 is a bottom plan view thereof.

The design involves the relationship of radio cabinet and base as shown on the drawing in solid lines, the base carrying a drawer; and, as shown by the dotted lines, having figures ornamenteally disposed thereon.

I claim:

The ornamental design for a combined radio and lamp, as shown and described.

MAURICE RESS.
